UNITED STATES PATENT OFFICE.

RICHMOND M. McGEE AND WILLIAM M. JONES, OF DALLAS, TEXAS.

AUTOMATIC RAILWAY-SWITCH.

No. 878,822.

Specification of Letters Patent.

Patented Feb. 11, 1908.

Application filed July 1, 1907. Serial No. 381,728.

To all whom it may concern:

Be it known that we, RICHMOND M. McGEE and WILLIAM M. JONES, citizens of the United States, and residing at Dallas, county of Dallas, State of Texas, have invented certain new and useful Improvements in Automatic Railway-Switches; and we do hereby declare the following to be a full, clear, and exact description of the invention, such as will enable others skilled in the art to which it appertains to make and use the same.

This invention relates to automatic railway switches of the general type illustrated in the application of Richmond M. McGee, one of the inventors herein, filed October 15, 1906, Serial No. 339,044, and is intended essentially as an improvement in the switch operating mechanism described and claimed in the said application.

The invention is illustrated in the accompanying drawings, in which:

Figure 1 is a plan view of the entire switch mechanism; Fig. 2 is an enlarged plan view of the apparatus immediately adjacent to the switch points; Fig. 3 is a side elevation of the track-trip for setting the sliding actuator rails; Fig. 4 is a side elevation of a portion of the detector bar and the coöperating means for locking the switch points, semaphore and locking pins; Fig. 5 is a sectional elevation of the sliding rail for actuating the switch points in one direction; Fig. 6 is a side elevation showing the sliding rail and coöperating mechanism for operating the locking pins; Fig. 7 is a similar view of the same apparatus showing the sliding rail in position to be engaged by the wheels; Fig. 8 is an enlarged detail, in plan view, illustrating a simple form of the interlock between the switch shifting means and the means for operating the locking pins; Fig. 9 is an elevation of a semaphore to indicate the condition of the locking mechanism; Fig. 10 is an enlarged detail of a bell-crank lever for reversing the locking pins to permit the switch to be automatically opened after a train has entered the siding.

Referring to the drawings, 1, 2 indicate the main rails of the track, and 3, 4, the switch points which control the turn-out or siding. The points 3, 4 are connected by a tie-bar 5, which operates in a stationary channel bar 6, and, in order to hold this switch in its respective positions, there are mounted upon one side of the channel bar two pins 7 and 8, which are adapted to be

projected by springs 9 and 10, respectively, to engage one or the other of the registering sockets or recesses in the tie-bar 5, in a manner quite similar to the corresponding apparatus shown in the application of McGee, hereinbefore referred to.

Mounted adjacent to the rail 2, and in advance of the switch points, is a sliding rail 40, which is normally retracted from engagement with the rail 2 by suitable springs, but is adapted to be brought up into position close against the rail 2, by means of a track-trip 60, which is engaged by a suitable detent carried by the engine or car and adapted to be moved into position to engage said trip 60. Said trip 60 is connected to a sliding rail 40 by means of a link 62, bell-crank 62', pull-rod 63, bell-crank 64, and pull-rods 65, so that when the trip 60 is depressed by the detent on the engine or car the sliding rail 40 is moved up close against the rail 2, as indicated in Fig. 7.

Sliding rail 40 is rigidly connected to a hook-rod 42 by means of a post 41, and an angularly disposed hook-member 47 on the forward end of said rod 42 has a beveled nose which engages with an incline 46 on a base-plate 45, to cause said end 47 to be elevated and pass behind a pivoted latch 44 mounted upon pull-rod 43, in the manner clearly indicated in Fig. 7, thereby positively connecting said sliding rail 40 with pull-rod 43. In order to hold said latch 44 in proper position, and also to permit said latch to move freely to permit hook 47 to slide under the same, the rear end of said latch is provided with a spring 48, which is mounted between the same and a sliding shoe 49 operating on the top of the rod 42, said shoe being connected by a link with latch 44, as indicated in Figs. 6 and 7.

Rod 43 is connected with a bell-crank 43' which, in turn, is connected with bell-crank 14 adjacent to the switch points by means of a rod 15. Said bell-crank 14 is connected to a pull-rod 11, located transversely of the track, which, in turn, is connected by bell-cranks 12 and 13 with locking pins 8 and 7, respectively, so that when the first wheel of a car or engine passes between sliding rail 40 and rail 2, said sliding rail is moved outwardly in a horizontal direction and exercises a direct pull on hook-rod 42, rod 43, through the connecting latch 44, and rod 43 acting through bell-crank 43', rod 15, bell-crank 14, rod 11, and bell-cranks 12 and 13,

retracts pin 8 from the registering sockets in tie-bar 5 and channel-bar 6, and tends to force pin 7 forward to engage in the other socket in tie-bar 5, when the switch points have been shifted to open the siding. It will be understood, of course, that the pins 7 and 8 serve to lock the switch points in their open and closed positions, respectively.

After locking pin 8 has been withdrawn, 10 the switch points may be thrown to permit the car or train to pass upon the siding, and the following automatic means are provided for shifting the switch points to appropriate position to effect this result. Between sliding rail 40 and the switch points, there is 15 located a second sliding rail 50, which may, of course, be of the same general construction as said sliding rail 40, but may be conveniently constructed as shown in Figs. 1 20 and 5, in which said sliding rail 50 is shown connected with pull-rod 63 of the track-trip 60 by bell-cranks 66 and rods 67, so that when said track-trip is depressed sliding rail 50 is likewise moved up against the side of 25 rail 2 in position to be engaged by the wheels of a car or engine. As in the construction and operation of sliding rail 40, it is also designed to connect sliding rail 50 with certain 30 operating mechanism, when said sliding rail is moved up adjacent to the rail 2.

Referring to Fig. 5, 52 is a pivoted weighted lever mounted behind and below sliding rail 50 in a suitable base-piece 53. A ratchet 54, connected to pivot 57 of the lever 35 52, normally lies below sliding rail 50, but when said sliding rail 50 is moved up into position against rail 2, the weighted end of the lever 52 throws ratchet 54 up behind said sliding rail 50, so that when the latter is 40 moved away from the rail by the flange of a wheel, said lever 52, ratchet 54, and pivot 57 are moved in the same direction, until the weighted end of said lever 52 engages an incline 58 on the support 53, which tilts the 45 lever 52 in the opposite direction causing its forward end, which is connected by spring 56 with ratchet 54, to retract said ratchet from engagement with the rear face of the sliding rail 50. Attached to the pivot 57 of 50 the ratchet 54 and lever 52, is a pull-rod 59, which is connected by bell-crank 59', pull-rod 20, and bell-crank 19, with a slide 16 which, in turn, is connected with tie-bar 5 in such manner that when said sliding rail 55 50 is moved outward by the flange of a wheel, said tie-bar is moved to shift the switch points to open the siding to a train, and immediately the switch points have been shifted locking pin 7 drops into the appropriate recess in said tie-bar 5 and holds the points in their adjusted position.

It will thus be noted that sliding rails 40 and 50 are simultaneously moved into position against the rail 2 by the depression of 60 the track-trip 60, when it is desired to pass

a train onto the siding or turn-out, and the movement of said sliding rails 40 and 50 toward the rail 2 serves to temporarily connect said sliding rails with the lock-pin operating means and the switch point actuating means, respectively, and immediately the flange of the leading wheel of a car or locomotive has passed between said sliding rails 40 and 50 and the track rail 2, said sliding rails are moved outwardly to their inoperative positions and automatically disconnected from the lock actuating and switch operating means.

It has been found desirable to prevent the 70 improper actuation of locking pins 7 and 8 and the tie-bar 5, and to effect this there is 75 provided an interlock between rod 11, which operates the pins 7 and 8 and the rod 16, which actuates tie-rod 5, such interlock being illustrated in detail in Fig. 8.

Referring to Figs. 1 and 8, it will be noted that the bell-crank lever 19, which shifts tie-bar 5, to open the switch to the siding, is connected to a bar 16 which has at one end a pin 19 engaging a slot 18 in said tie-bar 5, which normally occupies the position shown in Fig. 8, when the main line is open. Bars 11 and 16 are substantially parallel, and each is provided with V-shaped notches 22 and 23, respectively, the notched 90 ends of said bars being appropriately guided in a base-plate 29, in a cross-slot of which operates a general lozenge-shaped interlocking bolt 21, which is adapted to engage one or the other of the slots 22 or 23 in the bars 95 16 and 11, respectively, and prevent the bar so engaged being actuated until the other bar has been moved into position so that its slot lies opposite said bolt 21. In Fig. 8, the 100 parts of the apparatus are represented in a position they normally occupy with the main line open, and it will be noted that bolt 21 engages notch 22 in bar 16, so that the tie-bar 5 can not be moved to throw the switch and open the siding until bar 11 has 105 been moved into position so that its notch 23 lies opposite the bolt 21. The necessary movement is imparted to bar 11, when sliding rail 40 has been actuated to operate the locking pins 7 and 8 to unlock the switch. The subsequent operation of the sliding rail 110 50 operates rock-lever 19, as hereinbefore explained, which advances bar 16, which forces bolt 21 into engagement with notch 23 of the said bar 11, and holds the latter 115 positively locked for the time being. The forward movement of bar 16 advances the tie-bar 5 and throws the switch points to open the siding.

In order to release the interlock between 120 bars 11 and 16, to permit the switch to be moved to normal position after the train has entered the siding, the pin and slot connection between bar 16 and tie-bar 5, is provided. To permit the switch to be returned 125 130

110 to an extension of rod 20, which, as hereinbefore described, is directly connected to bell-crank 14 which actuates the locking pins 7 and 8 through rod 11.

5 Sliding rail 117 is connected by pull-rod 118, bell-crank 119, tie-rod 120, and bell-crank 121 directly with the tie-bar 5. Sliding rail 115 is mounted somewhat in advance of rail 117, which permits the pins 7 and 8 to be shifted before the wheels reach sliding rail 117 to shift the tie-bar 5 and the switch points connected thereto.

Briefly described, the operation of the apparatus is as follows: When a train approaches the switch to take the siding, the engineer or other operator depresses the detent on the locomotive to engage trip 60, which moves sliding rails 40 and 50 into position against rail 2, so that said sliding rails will be engaged by the wheels of the locomotive and forced outwardly. The inward movement of said sliding rail 40 locks it temporarily to the actuating means for locking pins 7 and 8, and similarly the inward movement of sliding rail 50 locks the same temporarily to the switch point actuating means. As the leading wheels of the engine pass between said sliding rails 40 and 50, they are, as described, forced outwardly first shifting the locking pins 7 and 8, and immediately thereafter advancing said tie-bar 5 to throw the switch points to open the siding. The movement of sliding rails 40 and 50, under the influence of the wheel flanges, disconnects said sliding rails from rods 43 and 59, respectively, and leaves said sliding rails and track-trip 60 in their normal positions to be again operated by a succeeding train desiring to enter the siding. Immediately after the train passes sliding rail 50, it passes over detector bar 70, and if pin 7 has not been forced into its coöperating socket in tie-bar 5, said detector-bar is elevated and the wheel tread engages the same and forces said locking pin home, thereby insuring the proper relation of the switch points, and, inasmuch as the detector bar cannot again rise above the head of rail 2, it will be apparent that the relation of the locking pins cannot be changed

has been effected, however, the weighted lever 26 moves rod 11 forward and shifts pins 7 and 8, retracting 7 and advancing 8, and practically simultaneously therewith spring 99 throws the switch points to normal position, viz., to open the main line, as shown in Figs. 1 and 2.

What we claim is:

1. In an automatic railway switch, the combination with a movable switch member, 75 of a shifting bar therefor, means coöperating with said bar for positively locking the switch in open or closed position, normally retracted sliding rails for operating the locking mechanism and shifting the switch, respectively, and a car actuated trip for moving the sliding rails into position to be engaged by the car wheels.

2. In an automatic railway switch, the combination with a movable switch member, 85 of a shifting bar therefor, means coöperating with said bar for positively locking the switch in open or closed position, normally retracted laterally sliding rails for operating the locking mechanism and shifting the 90 switch, respectively, and a car actuated trip for moving the sliding rails into position to be engaged by the car wheels.

3. In an automatic railway switch, the combination with a movable switch member, 95 of a shifting bar therefor, locking pins for positively holding the switch in open and closed position, laterally sliding rails for operating the locking pins and shifting the switch, respectively, a car actuated trip for 100 moving said sliding rails into position to be engaged by the car wheels, and means for automatically connecting the sliding rails with the bolt operating and switch actuating mechanism, respectively, when said sliding 105 rails are moved to position by the trip and for disconnecting said parts after said sliding rails have been moved by the wheels.

4. In an automatic railway switch, the combination with a movable switch member, 110 of a shifting bar therefor, locking pins for positively holding said bar in both positions of said switch, a normally inoperative sliding rail for operating said locking pins, a normally inoperative sliding rail for actuating the 115

and the wheels, as hereinbefore described, will depress the detector bar and force the appropriate pin home into locking position.

As an additional means to secure the switch 60 points in both positions, there is provided a rod 91, connected to tie-rod 90, which joins the extreme ends of the switch points, which rod 91 passes through a stationary chair 77 below the tie-rod 75, and mounted upon said 65 tie-rod 75 is a pin 76 which engages register-

for shifting the tie-bar 5 and connected switch points. Both of these sliding rails 115 and 117 normally lie against the main rails of the siding, when the switch points are in position to hold the main line open, but are moved away from said rails of the siding when the switch points are in position to open the siding. Sliding rail 115 is connected by pull-rod 116, bell-crank 114, tie-rod 113, bell-crank 112, link 111, bell-crank 125
